MOISTENING APPARATUS

John O. Ross, New York, N. Y., assignor to J. O. Ross Engineering Corporation, New York, N. Y., a corporation of New York

Application January 12, 1943, Serial No. 472,176

4 Claims. (Cl. 68—5)

This invention relates to increasing the moisture content of water-absorbent material. A specific embodiment of the invention pertains to increasing the water content of a strip of fabric of low tensile strength.

An object of this invention is an apparatus for providing a low tensile strip of water-absorbent material with a predetermined moisture content uniformly distributed throughout the material in the shortest possible time and while the material is kept free from tension.

According to this invention, moisture is added to the strip by continuously feeding it into and out of a chamber in which it is contacted with hot humid air and maintaining the strip before and after passage through said chamber at a temperature below the temperature of the contacting air. For example, by impinging the strip with a conditioned air stream of 95° F. temperature and 90% relative humidity, the strip being of approximately 75° F. temperature, a surface deposit is formed on the strip in the matter of a very few seconds and the temperature of the strip is brought up very close to the dew point temperature of the air. From then on, moisture can be absorbed into the strip only by the slow process of approaching equilibrium. The moisture provided by the surface deposit usually is less than is required to give the strip the desired moisture content. Therefore, to supply the desired moisture content to the strip, the strip, after being subjected to the treatment above described, is cooled to approximately its original temperature under conditions such as to prevent appreciable evaporation of the deposited moisture and then the above-described treatment with hot humid air is repeated. Preferably, the strip is cooled by impinging with cold air of high humidity but may be cooled by other suitable means. The strip is subjected to repeated cycles of the treatment above described until it reaches the desired moisture content. Each treatment of the cooled strip with hot humid air is effected in a short period while each cooling operation likewise requires only a short period so that in the matter of a few seconds the strip is brought to the desired moisture content as only a relatively few passes of the strip through the hot humid air is required to provide it with the desired moisture content. In order to support the strip free from tension during the moistening operation, a succession of conveyors is provided for supporting the strip during its subjection successively to the hot humid atmosphere and cooling it between such treat-

ments. The conveyors are positively driven and the strip lies thereon so that it is not subject to any tensile strain during the addition of moisture thereto.

Other objects, novel features and advantages of this invention will become apparent from the following specification and accompanying drawing, wherein the single figure of drawing illustrates schematically one form of apparatus for treating strip material according to the invention.

The treating chamber 10 is divided into a cooling compartment 11 and a moistening compartment 12. In each compartment are provided several rolls 13 on which are supported conveyors 14, each of which is arranged partly in compartment 11 and partly in compartment 12. The partition 15 which divides the chamber 10 into the compartments 11 and 12 is provided with apertures 16 through which the conveyors pass. Drive means 17 are provided for rotating the rollers 13 to cause feeding of the conveyors 14.

In the cooling chamber 11 is provided a plurality of ducts 18 each overlying the top reach of one conveyor. In the moistening chamber 12 is provided a plurality of ducts 19 each arranged above the upper reach of a conveyor. Both the ducts 18 and 19 are supplied with a large number of relatively small apertures through which air may be discharged toward the underlying conveyor. A supply duct 20 is provided for delivering cold humid air to the ducts 18 and a supply duct 21 is provided for delivering hot humid air to the ducts 19.

An apparatus 22 of standard construction is provided for supplying cold and preferably moist air of proper temperature to the duct 20 and an apparatus 23 of standard construction is provided for supplying to the duct 21 air having the proper moisture content and of the proper temperature. An exhaust duct 24 common to both compartments is provided for discharging air from such compartments. The strip of material S to be treated is supplied through an opening 25 in one wall of the compartment 11 onto the upper reach of the top conveyor and is advanced successively by the top conveyor and the remaining conveyors alternately through the compartments 11 and 12 and is finally discharged from the bottom conveyor through the aperture 26 in the wall of compartment 11. The strip S thus passes at a predetermined rate back and forth in several reaches through the two compartments and after its last passage through the cooling compartment

is discharged from the treating apparatus to suitable take-up mechanism, not shown. From the duct 20 cold moist air of a predetermined temperature is supplied to the ducts 18 and through the duct 21 heated air of predetermined air and moisture content is supplied to the ducts 19. The air thus supplied is caused to impinge on both sides of the strip as it travels through the apparatus.

In normal operation of the apparatus, the strip S is first brought to a predetermined temperature in the compartment 11, for example, 75° F. and then is carried into the compartment 12 where it is subjected to air preferably of 95° F. and 90% relative humidity. The strip is then returned to the cooling chamber where its temperature is reduced and the cycle above described is repeated a predetermined number of times. During its various passes through the moistening chamber, a surface film of moisture is deposited on the strip due to the fact that its temperature is below the dew point temperature of the air supplied to the ducts 19 and the temperature of the strip is brought up very close to the dew point temperature of the air. After the temperature of the strip has nearly reached the dew point temperature of the air no further moisture will be deposited on the strip except by the slow process of approaching equilibrium. The deposit of the surface film and the elevation of the strip temperature to nearly the dew point temperature of the air takes place in a matter of a few seconds and the strip speed and the length of its path in the compartment 12 is so determined that it remains in the compartment only long enough for such effects to be accomplished. The strip absorbs the deposited moisture and is then returned to the compartment 11 for cooling and appreciable evaporation of moisture from the strip is prevented by the humid condition of the cooling air. Through successive treatments, the strip absorbs enough increments of moisture to provide it with the desired moisture content in comparatively short time as the alternate passages of the strip through the cooling chamber and moistening chamber require only a few seconds each.

It is of course understood that various modifications may be made in the apparatus and procedure above described without in any way departing from the spirit of the invention as defined in the appended claims.

I claim:

1. Apparatus for moistening a continuously moving strip of water-absorbent material comprising a horizontally elongated housing divided by a vertical wall into a pair of chambers, a plurality of superposed conveyors each common to both chambers and passing through restricted openings in said vertical wall, a first and a second opening in vertically spaced planes in an outer side wall of one of said chambers, the first of said openings being provided for the passage of said strip from the exterior of said housing to the first of said conveyors and the second of said openings being provided for withdrawing it from the last of said conveyors to the exterior of said housing, means for driving successive conveyors in opposite directions, the delivery end of each conveyor except the last one being so positioned as to discharge said strip to the next conveyor, means for supplying cold humid air to said strip in one chamber and means for supplying hot humid air to said strip in the remaining chamber.

2. Apparatus for moistening a continuously moving strip of water-absorbent material comprising a horizontally elongated housing divided by a vertical wall into a pair of chambers, a plurality of superposed conveyors each common to both chambers and passing through restricted openings in said vertical wall, a first and a second opening in vertically spaced planes in an outer side wall of one of said chambers, the first of said openings being provided for the passage of said strip from the exterior of said housing to the first of said conveyors and the second of said openings being provided for withdrawing it from the last of said conveyors to the exterior of said housing, means for driving successive conveyors in opposite directions, the delivery end of each conveyor except the last one being so positioned as to discharge said strip to the next conveyor, ducts in each chamber arranged above the conveyors, each of said ducts having apertures adapted to direct air toward said strip on the underlying conveyor, means for supplying cold humid air to the ducts in one chamber, and means for supplying hot humid air to the ducts in the remaining chamber.

3. Apparatus for moistening a continuously moving strip of water-absorbent material comprising a horizontally elongated housing divided by a vertical wall into a pair of chambers, a plurality of superposed conveyors each common to both chambers and passing through restricted openings in said vertical wall, a pair of openings in vertically spaced planes in an outer side wall of one of said chambers, the upper of said openings being provided for the passage of said strip from the exterior of said housing to the upper of said conveyors and the lower of said openings being provided for withdrawing it from the lower of said conveyors to the exterior of said housing, means for driving successive conveyors in opposite directions, the delivery end of each conveyor except the lower one being so positioned as to discharge said strip to the next lower conveyor, means for supplying cold humid air to said strip in one chamber, and means for supplying hot humid air to said strip in the remaining chamber.

4. Apparatus for moistening a continuously moving strip of water-absorbent material comprising a horizontally elongated housing divided by a vertical wall into a pair of chambers, a plurality of superposed conveyors each common to both chambers and passing through restricted openings in said vertical wall, a pair of openings in vertically spaced planes in an outer side wall of one of said chambers, the upper of said openings being provided for the passage of said strip from the exterior of said housing to the upper of said conveyors and the lower of said openings being provided for withdrawing it from the lower of said conveyors to the exterior of said housing, means for driving successive conveyors in opposite directions, the delivery end of each conveyor except the lower one being so positioned as to discharge said strip to the next lower conveyor, ducts in each chamber arranged above the conveyors, each of said ducts having apertures adapted to direct air towards said strip on the underlying conveyor, means for supplying cold humid air to the ducts in one chamber, and means for supplying hot humid air to the ducts in the remaining chamber.
